Howard C. Meyer
BY William B. Jensen

ATTORNEY

UNITED STATES PATENT OFFICE

HOWARD C. MEYER, OF ASPINWALL, PENNSYLVANIA

SIGN

Application filed September 17, 1931. Serial No. 563,251.

This invention relates to price signs which are particularly useful for indicating the daily price of gasoline, it being among the objects of the invention to provide a sign of a permanent character in which part of the indicia is a permanent part of the sign itself and a part is interchangeable, such interchangeable or renewable parts being of the same general appearance as the permanent parts.

A further object of the invention is the provision of means for rendering certain characters or indicia of the signs readily removable without the use of tools or without requiring the fastening and unfastening of screw members.

Another object of the invention is the provision of a cast metal sign which is designed to be of substantially uniform cross-section to prevent warpage of the casting when the metal cools.

A further object of the invention is the provision of price signs of the above designated character which shall be of an ornamental character designed to aid in improving the appearance of gasoline dispensing stations and be of such proportion and design as to indicate at a glance the brand of gasoline dispensed at any particular station and the price of such gasoline.

The invention will become more apparent from a consideration of the accompanying drawings constituting a part hereof in which:

Figure 1 is a front elevational view of price sign embodying the principles of this invention;

Figure 2 a cross-sectional view along the line II—II of Figure 1.

Figure 3 an enlarged cross-section of the upper portion of the sign;

Figure 4 a side elevational view of the interchangeable characters;

Figure 5 a cross-section through the body of the casting showing perforations for mounting the characters; and

Figure 6 a sectional elevation illustrating the attachment of the characters to the sign.

With reference to the several figures of the drawings, the structure therein illustrated comprises a casting generally designated at

1 having its top portion 2 of an ornamental character, and having its edges raised, with the letters or indicia 3 in relief. The top portion 2 may be employed to designate the brand of gasoline by having the name of the brand or company cast integrally in the portion designated gasoline. The indicia—That good gasoline, Gas, Tax, and Total is permanently cast in the sign and is in relief in the manner shown in Figure 2. The price occurring in line with the gas, tax and total such as the prices 12, 3, and 15, are not a permanent part of the sign but are detachable and interchangeable in accordance with price fluctuations as they occur. However, the price characters are of the same size and type as the permanent indicia on the sign so that they appear as a permanent part of the sign.

On account of the sign being a casting and of substantial dimensions, it must be formed of relatively thin cross-section and to prevent warpage due to unevenness in the metal cooling, it is essential that the cross-section of the sign be substantially uniform throughout. To provide for this, the indicia are hollow and of the thickness of the body of the casting as is clearly shown in Figure 2 of the drawings. For example, the section of Figure 2 is taken through the center line passing through the reference characters O and L and shows that the letter O and the letter L are of the same thickness as the body of the sign.

The sign is designed to be mounted on the wall of a building by attaching means such as screws or nails disposed through the corner openings 4 and to assure that the interchangeable characters are secure on the sign, an off-set portion 5 is provided at the lower edge to hold it on a slant.

The body 6 of the sign is preferably spaced from the frame or outer edge 7 so as not to interfere with the mounting of the sign although this is not essential.

As previously stated, the price numerals herein designated by the reference character 8 are interchangeably mounted on the sign in a manner to render them detachable without the aid of tools. The characters are provided

with pin-like projections 9 and 10, the projection 10 being bent or curved and being the fastening means at the top of the character 8.

The sign is provided with perforations located in the body 6 in line with the indicia with which it cooperates. On account of the curved hook-like projections 10 of the character, the perforations in which these hook members are disposed are counter-sunk as shown at 11, the counter-sink extending to within a short distance of the front of the sign to permit the hook-like projection being entered therein. The bottom perforation 12 for receiving the pin 9 is not counter-sunk.

13 To assemble the numeral 8, the curved projection 10 is first inserted in the opening, and the straight pin like member 9 is then placed in its perforation leaving the character mounted in the manner shown in Figure 6.

14 In this position the characters will not drop off, and cannot be accidentally brushed from the sign without being lifted in the same manner in which they were assembled, namely, by raising the bottom portion and then withdrawing the curved member 10 from the counter-sunk perforation. This interlock together with the provision of the projecting ledge 5 at the bottom of the sign holding the sign at a slight angle assures that the price characters remain on the sign undisturbed and permits of the ready assembling and changing of the price characters from day to day in accordance with the fluctuations of the prices.

15 On account of the hollow characters and uniform cross-section of the sign, a perfectly straight casting is produced as all of the metal is cooled at a uniform rate thereby preventing the setting up of stresses which cause warping when the metal is of uneven thickness.

16 By utilizing the interchangeable price characters with a substantially thin section of metal in the sign, such a sign can be produced at reasonable cost and provides a decorative structure around gasoline stations which at the same time is readily visible to motorists at a considerable distance. Two of such signs may be mounted on the corners 50 of a gasoline dispensing station so as to render them visible from approaches on either side of the building.

17 A sign of the above described character is particularly useful as it saves the replacement of the printed forms heretofore employed. It is now a requirement in most States that gasoline dispensing stations permanently display price signs designating the cost of gasoline and by means of the present invention, this can be accomplished at a reasonable cost and with the further advantage that the signs of large companies having a large number of dispensing stations will all be uniform.

18 I claim:

1. A sign for gasoline stations comprising a metal casting having the indicia consisting of raised letters cast integrally therewith and having interchangeable price characters mounted thereon, said casting having perforations arranged in pairs in alignment with the indicia with the top perforations countersunk on the rear of the casting, and said interchangeable characters having projecting lugs adapted to be disposed in said perforations with the top lug bent to engage the countersunk perforation.

2. A sign for gasoline stations comprising a metal casting having the indicia consisting of raised letters cast integrally therewith, said letters being off-set and of substantially the same cross-sectional dimension as the body of the casting.

3. In testimony whereof I have hereunto set my hand..

HOWARD C. MEYER.
